UNITED STATES PATENT OFFICE.

CHARLES E. BURKE, OF CARNEYS POINT, AND GEORGE BARNHART, OF WOODSTOWN, NEW JERSEY, ASSIGNORS TO E. I. DU PONT DE NEMOURS & COMPANY, OF WILMINGTON, DELAWARE, A CORPORATION OF DELAWARE.

TREATING APPARATUS.

1,399,102.

Specification of Letters Patent.

Patented Dec. 6, 1921.

Application filed April 27, 1920. Serial No. 377,060.

To all whom it may concern:

Be it known that we, CHARLES E. BURKE and GEORGE BARNHART, citizens of the Dominion of Canada and the United States, respectively, and residents of Carneys Point, county of Salem, and State of New Jersey, and Woodstown, county of Salem, and State of New Jersey, respectively, have invented a certain new and useful Treating Apparatus, of which the following is a specification.

This invention relates to apparatus for chemically treating materials, and more particularly to apparatus by the aid of which the material in question may be continuously treated, the present apparatus providing for the uninterrupted passage of the material therethrough, the constant supplying of the chemical necessary for the treatment desired, and the proper handling of the material and chemical while in the apparatus. The invention finds particularly advantageous application when embodied in nitration apparatus and, specifically, when embodied in apparatus for the nitration of oil, and therefore we describe it with more particular reference to the art of nitration; but, it will be understood that we do not restrict it thereto, nor to the illustrated embodiment. In nitrating, as usually practised, the material to be treated is treated in batches in a vessel of relatively large capacity, the nitrating acid being gradually added to the material, or vice versa, until an entire batch has been treated, and after the nitration is completed the entire batch held in the nitrator is separated or drowned. A great difficulty with this method is that the earlier-treated portions of the batch, although their treatment is completed, are allowed to remain in the vessel, and, so, are kept in contact with the strong acid, and so forth, until the treatment of the later-treated portions is completed; the result is that the earlier-treated portions suffer decomposition and are of inferior quality. Another difficulty is that the procedure entails frequent interruptions, with consequent loss of time and so forth; therefore to so far as possible reduce the number of interruptions, it has been the practice, as mentioned above, to use a vessel of relatively large capacity in order to treat a relatively large quantity of material before having to interrupt the work

and empty the vessel. This latter practice is, however, dangerous as in case of accident the large amount of material in the vessel is a great menace. The apparatus of the present invention eliminates these difficulties since it provides for the removal of the material immediately upon the completion of its treatment; it is of small capacity so that the amount of material that would be involved in any accident is reduced to a minimum; and it provides for the uninterrupted treatment of an unlimited quantity of material.

An object of the invention is to provide an apparatus for the continuous treatment of material, and more specifically it is to provide an apparatus for continuous nitration.

To this end, and also to improve generally upon apparatus of the character indicated, the invention consists in the various matters hereinafter described and claimed.

In the accompanying drawings:—

Figure 1 is a diametrical section of an apparatus embodying the invention, taken substantially on the line 1—1 of Fig. 2; 80

Fig. 2 is a plan view of the apparatus illustrated in Fig. 1;

Fig. 3 is an elevational view, with a portion of the outer wall of the container broken out, and portions of the inner walls sectioned, to show the interior construction, of an apparatus essentially similar to the apparatus shown in Fig. 1, but having modified feeding means; 85

Fig. 4 is a plan view of the apparatus illustrated in Fig. 3, and 90

Fig. 5 is an elevational view of the agitator, with the feeding means arranged as in the apparatus illustrated in Fig. 3.

Referring now to the drawings; and more particularly to Figs. 1 and 2:—

The container, designated generally as 1, comprises a preferably annular closed-bottom receptacle 2, within which is placed a second annular closed-bottom receptacle 3, 100 extending substantially to the bottom of the receptacle 2, of relatively small capacity, and having its walls spaced all about from the walls of the receptacle 2. The inner receptacle provides a reaction receptacle, or 105 nitrating compartment, and the outer receptacle constitutes a chamber for a temperature controlling medium, for example

cold brine. A pipe 4 entering the bottom of the receptacle 2 provides for the flow of brine into, or out of, the receptacle, as desired, while pipes 5 and 6 opening into the 5 receptacle 2 adjacent its top, and communicating with the divisions 2^a and 2^b on opposite sides of the receptacle 3, provide for the flow of brine out of, or into, the receptacle 2, these pipes 4, 5 and 6 being desirably 10 used for connection in circuit with any suitable brine-cooling means, as a cooling coil (not shown). By making the inner receptacle of annular form, it will be seen that we conveniently provide the large wall area 15 desirable for efficient cooling, even though the inner receptacle is, as desired, of small capacity; also we provide for the use of a centrally mounted rotatable agitator 12.

Pipes, 7 and 8, are arranged in communication with the inner receptacle 3, the one 20 for the introduction of the material to be treated, as oil, and the other for the introduction of the chemical, as nitric acid. These pipes are desirably arranged substantially 25 diametrically opposite and discharge into the lower portion of the receptacle 3; for example, and as here illustrated, they discharge into the receptacle at its bottom. In cases where force feeding is not resorted 30 to the pipes 7 and 8 are of a height to provide a hydrostatic head sufficient to insure that the receptacle 3 can, if desired, be substantially completely filled with liquid. In this way it is provided that the oil and acid 35 shall enter at the bottom of the receptacle and travel upward, the nitration taking place during the travel. A discharge pipe, as 9, communicating with the receptacle 3 above the inlets 7 and 8 is provided for the 40 outflow of the nitrated oil.

Preferably a vertical series of pipes, as 9, 10 and 11, with the pipes at increasing heights, respectively, is provided, each pipe 45 having a valve as 9^a or 10^a for closing it when it is desired that discharge occur from a higher pipe. This arrangement permits the ready determining of the time that any particular oil shall remain in the apparatus. That is, oils which are readily 50 nitrated can be drawn from the lowest pipe, while by drawing a more-difficultly nitrated oil from a higher pipe the time during which that oil is under treatment can be made greater than that for a more easily 55 nitrated oil.

The driven agitator, designated generally as 12, is preferably in the general character of a cylinder, being shown as of the basket type and comprising a suitable number, as 60 twelve, or vertical members 13 extending substantially to the bottom of the receptacle 3, and connected together at their bottoms by a ring 14 and at their tops by a spider 65 15. The spider 15 serves as a convenient means for mounting the agitator upon a

central shaft 16 to rotate therewith; the latter may be driven by any suitable means, for example the driving pulley 17, and may be supported in any suitable way, as by radial-and-thrust bearings 18 and 19 supported, respectively, by the base 20 and the container 1.

Conveniently, the inner receptacle 2 is supported from the outer receptacle by carrying the edges of the walls of one of the 75 receptacles over to the adjacent edges of the walls of the other, as indicated at 21 and 22, and connecting them thereto, thus not only supporting the inner receptacle but also closing the top of the outer receptacle. 80

In operation, the materials, as oil and nitric acid, are fed to the apparatus as required, this being conveniently done by any desired device (not shown) for automatically measuring the oil and acid and discharging them into the pipes 7 and 8, the agitator is rotated meanwhile at the speed desirable for the particular treatment, and the nitrated oil is continuously drawn off by the particular pipe 9, 10 or 11, corresponding to the desired time of treatment; in the meantime the receptacle 2 is filled with brine and brine circulated therethrough as required.

The structure illustrated in Figs. 3, 4 and 95 5, while essentially like that shown in Figs. 1 and 2, has provisions particularly adapting it for use when unusually intimate mixing of the oil and acid is called for. In this apparatus, the oil and acid pipes, as 7^a and 100 8^a, instead of being stationary, are carried by the agitator blades; thus, when the agitator rotates the pipes rotate therewith and the oil and acid are distributed along the 105 path of rotation. The pipes 7^a and 8^a extend substantially to the lower end of the agitator and so, like the pipes 7 and 8, communicate with the receptacle 3 at its lower portion and, for practical purposes, at its bottom. Their upper ends are carried radially inward to place them over the center 110 of rotation and thus permit their easy filling despite the rotation; as shown, one pipe, as 8^a, is carried fluid tight up through the funnel-like end 7^b of the other so that, if 115 desired, suitable feed pipes (not shown) can be readily led to the end 7^b and to the similar funnel-like end 8^b, without interference.

Any structural materials, suited to the particular materials to be handled, may be 120 used in the construction of the apparatus, for working with oil and nitric acid we have found cast or wrought iron satisfactory.

We claim:—

1. In a continuous treating apparatus, in 125 combination, an outer receptacle providing a chamber for a temperature-controlling medium, an inner reaction receptacle in the outer receptacle and spaced therefrom, means for introducing reacting materials 130

- into the inner receptacle and comprising a pair of reacting-material-introduction conduits, and means for withdrawing reaction products from such receptacle, said two 5 means, with respect to each other, communicating with the inner receptacle at points spaced therealong, and the said conduits of said introducing means both being spaced from said withdrawing means in the same 10 direction longitudinally of said reaction receptacle, whereby a pair of reacting materials can enter by said conduits and flow together along such receptacle toward said withdrawing means.
- 15 2. In a treating apparatus, in combination, an outer receptacle providing a chamber for a temperature-controlling medium, an inner reaction receptacle in the outer receptacle and spaced at its sides from the 20 sides of the outer receptacle to provide two chamber divisions, means for conducting a temperature controlling medium to the outer receptacle, and means for conducting such medium from such receptacle, said two conducting means communicating with the outer receptacle at points spaced therealong and at least one of such means being arranged, 25 relative to said two chamber divisions, for substantially immediate communication with both.
- 30 3. In a treating apparatus, in combination, an outer receptacle providing a chamber for a temperature-controlling medium, an inner reaction receptacle in the outer receptacle and spaced at its sides from the sides of the outer receptacle to provide two chamber divisions, means for conducting a temperature controlling medium to the outer receptacle, and means for conducting such 35 medium from such receptacle, said two conducting means communicating with the outer receptacle at points spaced therealong and both of such means being arranged, relative to said two chamber divisions, for substantially immediate communication with both.
- 40 4. In a continuous treating apparatus, in combination, an outer receptacle providing a chamber for a temperature-controlling medium, an inner reaction receptacle in the outer receptacle and spaced at its sides from the sides of the outer receptacle to provide two chamber divisions, means for introducing reacting materials to the inner receptacle and means for withdrawing reaction products from such receptacle, such two 45 means, relative to each other, being spaced along such receptacle to provide for continuous flow along the same, means for conducting a temperature controlling medium to the outer receptacle, and means for conducting such medium from such receptacle, said two conducting means communicating with the outer receptacle at points spaced 50 therealong and both of such means being
- arranged, relative to said two chamber divisions, for substantially immediate communication with both said divisions.
5. In a continuous treating apparatus, in combination, a reaction receptacle adapted to be vertically arranged, means for introducing reacting materials to the receptacle and comprising a pair of reaction-material-introduction conduits separately communicating with the receptacle at its lower portion, and means for withdrawing reaction products from the receptacle and communicating with the receptacle at its upper portion and above and spaced from the communication points of said conduits, whereby 70 a pair of reacting materials can separately enter by said conduits and flow upward together in said receptacle toward said withdrawing means, and the reaction product be withdrawn at said withdrawing means. 75
6. In a continuous treating apparatus, in combination, a reaction receptacle, means for introducing reacting materials to the receptacle and comprising a pair of reacting-material-introduction conduits, and means for withdrawing reaction products from the receptacle, said two means, with respect to each other, communicating with the receptacle at points spaced therealong, and the said conduits of said introducing means both 80 being spaced from said withdrawing means in the same direction longitudinally of said reaction receptacle, whereby a pair of reacting materials can enter by said conduits and flow together along such receptacle toward said withdrawing means, and said withdrawing means comprising a plurality of optionally usable exits spaced from each other along the receptacle thereby to serve as a means for controlling the time during 85 which the reacting materials and the product shall remain in said reaction receptacle. 90
7. In a continuous treating apparatus, in combination, a reaction receptacle adapted to be vertically arranged, means for introducing reacting materials to the receptacle adjacent the lower end thereof and comprising a pair of reacting-material-introduction conduits, and a plurality of devices adjacent the upper end of the receptacle for withdrawing reaction products from said receptacle and spaced along said receptacle from said means, the units of said plurality being vertically spaced from each other and certain of them including provisions for 100 optional closing and opening thereof whereby said plurality of exits serves as a means for controlling the time during which the reacting materials and the product shall remain in said reaction receptacle. 105
8. In a continuous treating apparatus, in combination, an outer receptacle providing a chamber for a temperature-controlling medium, an inner reaction receptacle in the outer receptacle and spaced at its sides from 110
- 115
- 120
- 125
- 130

- 4
- the sides of the outer receptacle to provide two chamber divisions for the medium, means for conducting such medium to the outer receptacle and means for conducting 5 such medium from such receptacle, said two means communicating with the outer receptacle at points spaced therealong and at least one of such means being arranged, relative to said chamber divisions, for substantially immediate communication with both, 10 means for introducing reacting materials to the inner receptacle, and means for withdrawing reaction products from such receptacle, said latter named two means, with respect to each other, communicating with the inner receptacle at points spaced therealong, then said withdrawing means comprising a plurality of exits spaced from each other along the inner receptacle, with certain of said exists including provisions for optional closing and opening thereof. 15
9. In a continuous treating apparatus, in combination, a reaction receptacle adapted to be vertically arranged, means for introducing reacting materials to the receptacle comprising a pair of reacting-material-introducing conduits and discharging into the receptacle at its lower portion, and means for withdrawing reaction products from the 20 receptacle and discharging therefrom adjacent its top portion, said introducing means including a device in the character of a vertically arranged pipe providing one of said conduits and of sufficient height to provide a 25 hydrostatic head corresponding to the height of said withdrawing means above the said lower portion of the receptacle.
10. In a continuous treating apparatus, in combination, a reaction receptacle adapted to be vertically arranged, means for introducing reaction materials to the receptacle and comprising a pair of reacting-material-introduction conduits discharging into the receptacle at its lower portion, and means 30 for withdrawing reaction products from the receptacle and discharging therefrom adjacent its top portion, said introducing means including a pair of devices each in the character of a vertically arranged pipe providing 35 a respective one of said conduits and of sufficient height to provide a hydrostatic head corresponding to the height of said withdrawing means above the said lower portion.
- 50 11. In a treating apparatus, in combination, a reaction receptacle, a rotatable agitator therein, and a pair of devices for introducing reacting materials to the receptacle and carried with said agitator to rotate therewith, said devices being separate and non-communicating whereby a pair of reacting materials may be separately and simultaneously introduced into said receptacle. 55
12. In a treating apparatus, in combination, a reaction receptacle, a rotatable agitator therein, and a pair of devices for introducing reacting materials to the receptacle, each of said devices being in the character of a pipe and each such pipe being mounted on said agitator to rotate therewith upon the axis thereof and having its receiving end in longitudinal alinement with such axis, one of said pipes, adjacent its receiving end, passing through the receiving end of the other. 60
13. In a treating apparatus, in combination, a reaction receptacle, a rotatable agitator therein, and a pair of devices for introducing reacting materials to the receptacle, each of said devices being in the character of a pipe and each such pipe being mounted on said agitator to rotate therewith upon the axis thereof and having its receiving end in longitudinal alinement with such axis, one of said pipes, adjacent its receiving end, passing through the receiving end of the other, and said pipes being separate and non-communicating whereby a pair of reacting materials may be separately and simultaneously introduced into said receptacle. 65
14. In a continuous treating apparatus, in combination, an outer receptacle for a temperature-controlling medium, an inner receptacle in the outer receptacle, spaced from the side walls thereof to divide the outer receptacle into inner and outer compartments, and extending to adjacent the bottom of the outer receptacle, means for circulating a temperature-controlling medium through said outer receptacle substantially throughout the length thereof and into and out of both its compartments, a pair of pipes for introducing reacting materials to the reaction receptacle, and a discharge device for withdrawing reaction products from the reaction receptacle, the discharge ends of said pair of pipes, and said discharge device, being spaced from each other longitudinally of said inner receptacle. 70
15. In a continuous treating apparatus, in combination, an outer receptacle for a temperature-controlling medium, an annular inner receptacle in the outer receptacle, spaced from the side walls thereof to divide the outer receptacle into inner and outer compartments, and extending to adjacent the bottom of the outer receptacle, means for circulating a temperature-controlling medium through said outer receptacle substantially throughout the length thereof and into and out of both its compartments, a pair of pipes for introducing reacting materials to the reaction receptacle, and a discharge device for withdrawing reaction products from the reaction receptacle, the discharge ends of said pair of pipes, and said discharge device, being spaced from each other longitudinally of said inner receptacle. 75
16. In a continuous treating apparatus, in combination, an outer receptacle for a tem- 80

- perature-controlling medium, an annular inner receptacle in the outer receptacle, spaced from the side walls thereof to divide the outer receptacle into inner and outer compartments, and extending to adjacent the bottom of the outer receptacle, means for circulating a temperature-controlling medium through said outer receptacle substantially throughout the length thereof and into and out of both its compartments, a pair of pipes for introducing reacting materials to the reaction receptacle, a discharge device for withdrawing reaction products from the reaction receptacle, the discharge ends of said pair of pipes, and said discharge device, being spaced from each other longitudinally of said inner receptacle, and an agitator in said reaction receptacle mounted for rotation concentrically therewith, and extending substantially the length thereof.
17. In a continuous treating apparatus, in combination, an outer receptacle adapted to be vertically arranged and for a temperature-controlling medium, an annular inner reaction receptacle in the outer receptacle, spaced from the walls thereof to divide the outer receptacle into inner and outer compartments, and extending to adjacent the bottom of the outer receptacle, means for circulating a temperature-controlling medium through said outer receptacle substantially throughout the length thereof and into and out of both its compartments, a pair of pipes for introducing reacting materials to the reaction receptacle, and having their discharge orifices at the bottom portion of such receptacle, a discharge device for withdrawing reaction products from the reaction receptacle and communicating therewith at the upper portion thereof, and an agitator in said reaction receptacle, mounted for rotation concentrically therewith, and extending substantially the length thereof.
18. In a continuous treating apparatus, in combination, an outer receptacle adapted to be vertically arranged and for a temperature-controlling medium, an annular inner reaction receptacle in the outer receptacle, spaced all about from the walls thereof to divide the outer receptacle into inner and outer compartments, and extending to adjacent the bottom of the outer receptacle, means for circulating a temperature-controlling medium through said outer receptacle substantially throughout the length thereof and into and out of both its compartments, a pair of pipes for introducing reacting materials to the reaction receptacle and having their discharge orifices at the lower portion of such receptacle, a discharge device for withdrawing reaction products from the reaction receptacle and communicating therewith at the upper portion thereof, and an agitator in said reaction receptacle, mounted for rotation concentrically therewith, and extending substantially the length thereof, said pair of pipes being carried by said agitator for rotation therewith and with their receiving ends adjacent the upper end of the agitator and their discharge orifices adjacent the lower end.

In testimony whereof we affix our signatures.

CHARLES E. BURKE.
